UNITED STATES PATENT OFFICE.

EDWARD HALL, OF LAURIUM, MICHIGAN.

CONDUIT-CLEANER.

1,338,917.

Specification of Letters Patent. Patented May 4, 1920.

Application filed November 18, 1919. Serial No. 338,898.

To all whom it may concern:

Be it known that I, EDWARD HALL, a citizen of the United States, and a resident of Laurium, in the county of Houghton and State of Michigan, have invented certain new and useful Improvements in Conduit Cleaners, of which the following is a specification.

My invention is an improvement in conduit cleaners, and has for its object to provide a device of the character specified, adapted for cleaning pipes of any character, as for instance flues, drains and the like, wherein a flexible shaft is provided with a circular brush connected to the shaft to rotate therewith, the shaft having a guiding wheel for properly spacing the brush with respect to the flue and for facilitating the insertion and the passage of the brush.

20 In the drawings:

Figure 1 is a side view showing the device in use,

Fig. 2 is a similar view of the brush and its support,

25 Fig. 3 is a sectional view.

In the present embodiment of the invention a brush is provided, consisting of bristles 1 which are arranged in circular form, and held between a pair of washers 2 of leather or the like. A central support 3 is provided for the bristles, midway between the washers, the said support being a ring preferably of brass, and a washer 4 of brass is arranged at the outer face of each leather 30 washer 2. The brush is held upon a threaded stem 5, between a shoulder 6 which separates the stem from the body 7 of the shaft section of which the stem is a part, and the body 8 of a yoke which is threaded on to 35 the stem.

40 Between the arms of this yoke there is

journalled a wheel 9, and the wheel, and the yoke are preferably of brass. The body 7 of the shaft section has a threaded socket 45 for receiving a stem 10 on another shaft section 11, which is also socketed to receive a stem 12 on a longer section 13. These sections 7, 11 and 13 are similar, and by means of them the rigid shaft which supports the brush and the wheel may be increased in 50 length or diminished as may be desired. The socket portion 14 of the shaft section 13 is detachable from the body portion. The body portion 13 has a plain stem 15 which engages a recess in the socket portion 14, and 55 the parts are pinned together by a cross pin 16. A flexible shaft 17 of usual construction is connected with the socket 14, for driving the brush.

50 In operation, for cleaning a chimney for instance, the brush and the wheel 9 are introduced through the stove pipe opening 18 of the flue 19. The shaft is now made to rotate, and the brush will rotate, cleaning the soot and other accretions from the flue 65 wall. The brush may be introduced as far as the flexible shaft will permit. In cleaning the drains the operation would be the same.

70 I claim:

A device of the character specified comprising a supporting shaft having a reduced threaded stem, a circular brush on the stem, a washer of flexible material on each side of the brush, rigid washers outside of the flexible washers, a yoke comprising a body having a socket into which the reduced end of the shaft is threaded and arms extending longitudinally of the shaft from the socket, and a wheel journalled between the arms.

75 EDWARD HALL.
